SPRING ASSEMBLY

David I. Levine, Lynn, Mass., assignor to Lissom-Melen Co., Lynn, Mass., a corporation of Massachusetts

Application November 2, 1937, Serial No. 172,363

5 Claims. (Cl. 5—273)

This invention relates to a spring assembly made up of a multiplicity of coil springs and more especially to an assembly wherein tie-wire or tie-wire elements are employed for assembling or tying together the springs into a unitary structure possessed of the desired integrity and the desired resiliency or spring action. The spring assembly hereof is designed for various purposes, for instance, as the resilient filling in mattresses, 10 cushions, and chair seats or backs, and as the foundation in various structures for sustaining a person comfortably in seated posture and/or at repose.

In the spring assembly hereof, wherein there are successive rows of juxtaposed coil springs and wherein the springs of one row are substantially aligned with the corresponding springs in the next row and the juxtaposed springs in one row are tied to the corresponding juxtaposed springs 20 in the next row, the tie-wire or tie-wire elements for tying together the juxtaposed springs in one row to the corresponding juxtaposed springs in the next row assume, accordant with the present invention, a special form highly advantageous for such purpose, namely, a form substantially straight excepting for loops protruding at spaced regions thereof, each of the loops being substantially S-configured and one of the hook portions of the S-configured loop engaging an end convolution of a coil spring and the other hook portion of the S-configured loop engaging an end convolution of a juxtaposed coil spring. Because the hook portions of the S-configured loop can readily be closed or clamped together sufficiently 30 to become for all practical purposes inseparably hooked onto the end convolutions of juxtaposed coil springs, it is hence seen that the invention hereof provides a simple and inexpensive spring assembly wherein the springs are hingedly interlocked to one another and are thus maintained in the desired substantially aligned or undistorted relationship while being freely compressible to afford the desired resiliency or spring action.

With the foregoing and other features and objects in view, the invention hereof will now be described in further detail with particular reference to the accompanying drawing wherein:

Figure 1 is a plan of a corner portion of a spring assembly embodying the invention hereof. 50 Figure 2 is an enlarged detailed section on the line 2—2 of Figure 1 and shows how juxtaposed springs in a row are hingedly interlocked.

Figure 3 illustrates in perspective a fragment of tie-wire used for the purposes hereof. 55 Figures 4, 5 and 6 depict the successive stages

of forming an S-configured loop in the tie-wire hereof.

Figures 7, 8 and 9 illustrate diagrammatically and conventionally the dies or instrumentalities serviceable for creating the wire forms or shapes 5 depicted in Figures 4, 5 and 6, respectively.

The tie-wire elements or units for the spring assembly hereof may be formed readily as wire is progressively being withdrawn from a coil accumulation or the like. As the wire is thus being 10 progressively withdrawn as a straight body, it may undergo at regularly spaced intervals a number of shaping operations designed to develop therein at such intervals S-configured loops 10 protruding from its otherwise straight body 11, as 15 appears best in Figure 3.

The first shaping operation may, as shown in Figure 7, involve passing the wire into a die 12 serving to create therein a loop or U-shaped bend 13, such as is depicted in Figure 4. The second 20 shaping operation may involve upsetting the loop or U-shaped bend 13, as by the die 14 indicated in Figure 8, so that the upper portions 13a of the loop retain their substantial perpendicularity to the straight wire 11 whereas the remainder 13b 25 of such loop is bent to a position of substantial perpendicularity to the portions 13a, as depicted in Figure 5. The third shaping operation may involve shaping the loop portions 13a and 13b in a multiple die 15, 16, such as is shown in Figure 30 9, which die serves to transform such loop portions into the S-configured loop 10 desired in the tie-wire hereof. It will be appreciated that the successive shaping or dieing operations are performed at successive stages of progress of the 35 wire 10 as it is progressively being withdrawn from an accumulation and that when the desired number of S-configured loops have been formed therein at appropriately spaced intervals, it may be cut into elements or units of a length suitable 40 for tying together all the aligned pairs of juxtaposed springs in the successive rows of a spring assembly.

The spring assembly wherein the tie-wire elements hereof are used may assume the particular 45 form illustrated in Figure 1. The assembly there appearing comprises successive spaced rows of juxtaposed compression coil springs 20 and 21, for instance, of the double-cone type. The assembly may be made by placing the coil springs, 50 as ordinarily, on a suitable block or form equipped with pins for holding the springs in the desired relationship as they are being tied together at their end convolutions by the tie-wire elements hereof. The tie-wire hereof is prefer- 55

ably of such length that it extends from a point X beyond the neighboring portions of a pair of juxtaposed springs in one marginal row to a point (not shown) beyond the neighboring portions of a 5 pair of juxtaposed springs in the opposite marginal row.

The tying together of the pairs of juxtaposed springs with their end convolutions in appropriately overlapping relationship in the successive 10 rows is accomplished by inserting the end convolution $20a$ of a spring 20 of a pair of juxtaposed springs into one of the hook portions $10a$ of an S-configured loop 10 and by inserting the end convolution $21b$ of the spring 21 of the same pair 15 into the other of such hook portions $10b$ of the same S-configured loop 10 . Once the end convolutions of the pairs of juxtaposed springs in the successive rows have been engaged in the successive S-configured loops 10 of a tie-wire, it is 20 a comparatively easy matter for the assemblyman to clamp together, as by pliers, the hook portions $10a$ and $10b$ of such loops so that such portions become in effect inseparably hooked onto the end convolutions, that is, without any tendency 25 in actual practice for the end convolutions to escape through the hook portions. Indeed, the hook portions $10a$ and $10b$ of the loop 10 may be brought together so closely to constitute, in effect, eyes through which the end convolutions 30 of the juxtaposed coil springs are threaded. Since the end convolutions of the juxtaposed coil springs are free to turn or rotate in the closed hook portions $10a$ and $10b$ when the spring assembly undergoes local compression, they may 35 be considered as being hingedly interlocked to one another by the tie-wires hereof, in consequence of which not only are the springs of the assembly maintained in the desired substantially aligned or undistorted relationship but the several 40 springs of the assembly and the assembly as a whole are freely and substantially noiselessly compressible and hence make for the desired resiliency or spring action in the various structures in which the spring assembly is used.

45 Each side of the spring assembly preferably includes the tie-wire elements hereof for tying together the end convolutions of juxtaposed springs in the successive rows, although it is possible to provide the tie-wires hereof on only one side of the assembly and to employ other forms of tie elements on the other side of the assembly.

If desired, the marginal or outermost portions 55 of the end convolutions of the border springs on either or both sides of the spring assembly hereof may be flexibly interlocked, as by helical wires 22, which are shown in Figure 1 as encompassing the marginal portions of the end convolutions of the border springs. The helical wires 22 thus 60 serve in the spring assembly hereof as rims or border elements tending to resist dislodgement or misalignment of the substantially aligned springs in the successive rows, especially when the assembly meets with blow or impact on the 65 intermediate convolutions of its border springs.

An important feature of the spring assembly hereof is that the juxtaposed coil springs of adjacent rows are so tied together by the tie-wires that while free compression of the springs readily 70 takes place and they are free to turn to a considerable extent at their end convolutions under compressing and distorting forces, nevertheless, such compression and turning movements are not accompanied by tendency for the springs to separate or loosen from one another, since the end- 75

convolution of one spring is firmly locked in place by the crimped hooked portion $10a$ of a tie-wire and the end-convolution of a juxtaposed spring is firmly locked in place by the crimped hook portion $10b$ of the same S-configured loop, indicated generally at 10 , in the tie-wire. It can be said, therefore, that the springs of the assembly hereof are hingedly interlocked by the tie-wires to one another for free compression and relative turning movement at their end-convolutions 10 while at the same time having no tendency to separate from one another during such compression and turning movement.

It is to be understood that the spring assembly and the tie-wires specifically described and illustrated are subject to variation and modification falling within the inventive principles hereof and, accordingly, that the protection to be afforded for the invention hereof should be ascertained from the appended claims whose terms should be construed as broadly as the prior art permits.

I claim:

1. In a spring assembly which comprises successive rows of juxtaposed coil springs and wherein the springs in one row are substantially aligned with the corresponding springs in the next row and the juxtaposed springs in one row are tied to the corresponding juxtaposed springs in the next row, tie-wires for tying together the juxtaposed springs in one row to the juxtaposed springs in the next row, said tie-wires being substantially straight excepting for loops protruding at spaced regions thereof, each of said loops being substantially S-configured and one of the hook portions of said S-configured loop engaging an end convolution of one of said coil springs and the other hook portion of said S-configured loop engaging an end convolution of a juxtaposed coil spring, the end convolutions of said juxtaposed coil springs being in overlapping relationship at their regions thus engaged by said S-configured loop.

2. In a spring assembly which comprises successive substantially regularly spaced rows of juxtaposed compression springs and wherein the springs in one row are substantially aligned with the corresponding springs in the next row and the juxtaposed springs in one row are tied to the corresponding juxtaposed springs in the next row, tie-wires for tying together in freely compressible relationship the juxtaposed springs in one row to the corresponding springs in the next row, said tie-wires being substantially straight excepting for loops protruding at substantially regularly spaced regions thereof, each of said loops being substantially S-configured and one of the hook portions of said S-configured loop being inseparably hooked onto an end convolution of one of said coil springs and the other hook portion of said S-configured loop being inseparably hooked onto an end convolution of a juxtaposed coil spring, the end convolutions of said juxtaposed coil springs being in overlapping relationship at their regions thus engaged by said S-configured loop.

3. In a spring assembly, the combination with successive rows of juxtaposed coil springs of tie-wires for tying together the juxtaposed springs in one row to the juxtaposed springs in the next row, said tie-wires comprising substantially S-configured loops protruding at spaced regions thereof, one of the hook portions of each said S-configured loop engaging an end convolution of one of said coil springs and the other hook portion 75

- of said S-configured loop engaging an end convolution of a juxtaposed coil spring, the end convolutions of said juxtaposed coil springs being in overlapping relationship at their regions thus engaged by said S-configured loop.
4. In a spring assembly, the combination with successive rows of juxtaposed coil springs of tie-wires for tying together in freely compressible relationship the juxtaposed springs in one row to the juxtaposed springs in the next row, said tie-wires comprising substantially S-configured loops protruding at spaced regions thereof, one of the hook portions of each said S-configured loop being inseparably hooked onto an end convolution of one of said coil springs and the other hook portion of said S-configured loop being inseparably hooked onto an end convolution of a juxtaposed coil spring, the end convolutions of said juxtaposed coil springs being in overlapping relation-
- ship at their regions thus engaged by said S-configured loop.
5. In a spring structure in which coil springs are arranged in pairs adjacent each other, means securing the end coils of said pairs of adjacent springs together against relative movement with the end coil of one spring of each pair of springs in overlapping relation to the end coil of the other spring of said pair, comprising a tie wire having straight portions resting at spaced points on the end coil of one spring of said pair and having a looped portion of generally S-shape extending from said straight portions partly around the end coil of the other spring of said pair of springs, then between the overlapped portions of said end coil, and then returned upon itself to partially encircle the overlapped portion of the end coil of said one spring.

DAVID I. LEVINE.
